UNITED STATES PATENT OFFICE

LOUISE PEDERSEN, OF BARRINGTON, ILLINOIS

EYE SHIELD

Application filed September 23, 1931. Serial No. 564,533.

This invention relates to improvements in eye shields preferably of an opaque structure adapted to removably hold a pad impregnated or saturated with a medicament or 5 lotion, to be placed over the eyes and secured in position for the purpose of treatment of the eyes to soothe and rest them, and for the purpose of other treatment of the eyes.

A further object is to provide in a device 10 of this character improved means for removably holding a pad in position and for securing and holding the shield to the head of the user.

To the attainment of these ends and the accomplishment of other new and useful objects as will appear, the invention consists in the features of novelty in substantially the construction, combination and arrangement of the several parts hereinafter more fully 20 described and claimed and shown in the accompanying drawing illustrating this invention, and in which

Figure 1 is a perspective view of a shield of this character constructed in accordance with 25 the principles of this invention, showing parts thereof partially separated.

Figure 2 is an elevation of one face of the shield.

Figure 3 is an elevation of the other face of 20 the shield.

Figure 4 is a view taken on line 4—4, Figure 2, showing parts partially separated.

Figure 5 is a sectional view on line 5—5, Figure 4, with parts omitted and on an ex- 35 aggerated scale.

The eye shield consists essentially of a body portion 10 constructed of any suitable flexible material preferably opaque, and the marginal edge 11 thereof is preferably formed 40 by folding over the material upon itself so as to produce a slightly raised portion and thereby form shallow cup shaped portions spaced from each other and on opposite sides of a reduced portion 12. This reduced portion is shaped so as to receive the bridge of the nose when the shield is placed across the eyes of the user.

The body portion 10 may be of any desired configuration and is of any desired size, and 50 is also preferably formed of waterproof ma-

terial. Perforated, rim like or flexible frame members 13 are secured to the body portion and these members are preferably formed of flexible waterproof material connected together by a connecting portion 14, and this 55 connecting portion 14 is adapted to be secured to the body portion 10 intermediate the cup shaped portions of the body. The frame members 13 are also preferably constructed of waterproof material and are preferably of a size and configuration to conform to the contour of the body portion, and when resting thereagainst are also of a size that the outer peripheral edges of the frame members 60 will preferably stand within the peripheral 65 edges of the body member.

Connected to the frame members 13 preferably at points opposite to the points at which they are secured to the body portion, are flexible members 15, preferably in the 70 form of ribbons or tapes, and each of these members 15 passes through a slot 16 in the body portion 10 preferably adjacent the outer extremities thereof. These slots may be formed in any suitable manner and when the 75 flexible members 15 are drawn taut, the frame members 13 will stand in close proximity to the proximate face of the body member 10.

The numeral 17 designates pads formed of 80 any suitable material such as absorbent cotton or the like, and these pads are preferably of a configuration to conform to the contour of the body portion and the frame members 13. One of these pads is provided for each of the cup shaped portions of the body and 85 is of a size and configuration to fit therein and beneath the frame members 13, so that when the pads are in position and the flexible member 15 drawn taut the pads will be held against displacement by means of the frame members, 90 and yet they may be removed when desired by raising the frame members.

In use, the pads 17 are saturated with a 95 medicament or lotion and then placed in the cup shaped portions of the body, after which the frame members 13 are drawn thereover. The shield may then be applied to the eyes of the user by placing the pad portion in contact with the eyelids, the opening in the frame members being sufficiently large for this pur- 100

pose. The shield may then be secured to the head of the user by passing the flexible members 15 around the head and tied or otherwise fastened together.

With this improved construction it will be manifest that by reason of the waterproof nature of the body portion 10 and the frame members 13, as well as the cup shaped portion of the body, the liquid will be prevented from running out of the shield and at the same time the shield will form a protection and will prevent the liquid from passing therethrough.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A flexible eye shield having a reduced portion intermediate its ends to fit over the bridge of the nose, perforated, rim like flexible frame members hingedly connected to said shield adjacent and on each side of the longitudinal center of the shield and adapted to extend over the eye covering portions of the shield, to form therewith holders for removable pads, and means for securing together the free portions of the said frames and the said shield.

2. A flexible eye shield having a reduced portion intermediate its ends to fit over the bridge of the nose, perforated, rim like flexible frame members hingedly connected to said shield adjacent and on each side of the longitudinal center of the shield and adapted to extend over the eye covering portions of the shield, to form therewith holders for removable frame members hingedly connected to the free portions of the said frames and the said shield, said shield being formed of opaque waterproof material.

3. A flexible eye shield having a reduced portion intermediate its ends to fit over the bridge of the nose, perforated, rim like flexible frame members hingedly connected to said shield adjacent and on each side of the longitudinal center of the shield and adapted to extend over the eye covering portions of the shield, to form therewith holders for removable pads, and means for securing together the free portions of the said frames and the said shield, said frame members being formed of waterproof material.

4. A flexible eye shield having a reduced portion intermediate its ends to fit over the bridge of the nose, perforated, rim like flexible frame members hingedly connected to said shield adjacent and on each side of the longitudinal center of the shield and adapted to extend over the eye covering portions of the shield, to form therewith holders for removable pads, and means for securing together the free portions of the said frames and the said shield, the said means also serving as an attaching means for the shield.

5. A flexible eye shield having a perforated, rim like flexible frame member connected to the shield, a portion of the frame member being free from the shield to permit of the insertion of a pad therebetween and removal therefrom, and a flexible member secured by one end to said free portion of the frame member, there being an opening through the shield through which said flexible member passes for securing said portion of the frame member and shield together and for holding the inserted pad against displacement, said flexible member also serving as a means for securing the shield to the head of the wearer, said pad contacting directly with the eye through the frame member.

6. An opaque flexible eye shield, perforated, rim like flexible frame members co-operating with the shield to form a space therebetween for the reception of a pad, and flexible elements secured to the frame member and passing through openings in the shield member for securing the two together to hold said pad in position, said flexible elements also serving as a means for securing the shield in position for use, said pads contacting directly with the eyes through the frame members.

7. A flexible eye shield, the marginal edge of which is raised to form a shallow pocket for the reception of a removable pad, a perforated, rim like flexible frame extending over the pocket for holding the pad against displacement, and flexible members connected with the frame and passing through openings in the shield for securing the frame and shield together, said flexible members also serving as a means for securing the shield in position for use.

8. A flexible eye shield, the marginal edge of which is raised to form a shallow pocket for the reception of a removable pad, a perforated, rim like flexible frame extending over the pocket for holding the pad against displacement, and flexible members connected with the frame and passing through openings in the shield for securing the frame and shield together, said flexible members also serving as a means for securing the shield in position for use, said shield being opaque, and said shield and frame being formed of waterproof material.

In testimony whereof I have signed my name to this specification, on this 16th day of September, A. D. 1931.

LOUISE PEDERSEN.
